BEAM-SWITCHING TUBE COUNTER WITH TRANSISTOR AMPLIFIER GENERATING CARRY PULSE, DEPENDENT ON THE CONFIGURATION OF THE SPADE ELECTRODES

Arpad Somlyody, Raritan, N.J., assignor to Burroughs Corporation, Detroit, Mich., a corporation of Michigan

Filed Sept. 24, 1962, Ser. No. 225,644

3 Claims. (Cl. 315—8.5)

This invention relates to electronic counting circuits and particularly to counting circuits using multi-position magnetron beam switching tubes as the counting elements thereof.

Magnetron beam switching tubes include an electron-emitting cathode and a plurality of groups of electrodes, each of which is adapted to receive an electron beam from the cathode and to provide an output signal therefrom. Each group of electrodes includes a target electrode, from which an output signal is provided and which receives the electron beam, a spade electrode which forms and holds an electron beam on its associated target electrode, and a switching electrode which may be used to switch an electron beam from one group of electrodes to the next. The spade electrodes may also be utilized to perform this switching function. The tube performs a counting operation as an electron beam moves from position to position within the tube.

A counting circuit of the type contemplated by the present invention includes a plurality of beam switching tubes coupled together to provide a plurality of series-connected counting stages. As one tube completes a counting operation, a carry pulse is transmitted to the next tube to register a count therein. In such counters using beam switching tubes, it is customary to couple each counting tube to a carry transistor which provides the desired carry pulse at its output or collector electrode. Generally, the output of this transistor is coupled to the driving circuit for the next counting tube.

It has been found that the various circuit elements which are thus required and which are coupled to the output of the carry transistor represent a considerable capacitance adversely affects the speed of recovery of the collector electrode after it has performed its function of generating a carry pulse. Thus, the speed at which each counting tube can be operated is limited by the ability of the collector electrode of the carry transistor to produce a carry pulse when the tube has completed its counting cycle.

In addition, the carry pulse generated by one counting tube and applied to the next counting tube in a counting chain must be of sufficient duration so that it can be properly registered in said next counting tube. Thus, a balance must be established between the time during which the carry transistor is generating a carry pulse and the time during which it is prepared for generating the next carry pulse.

Accordingly, the objects of the present invention are concerned with the provision of an improved electronic counting circuit using magnetron beam switching tubes as the counting units thereof and having improved means for controlling the generation of carry pulses.

The present invention is applicable to a counting circuit which includes, briefly, a plurality of series-connected

2

counting stages, with each stage including a multi-position magnetron beam switching tube as the counting element thereof. In each counting tube, a selected counting position in the counting cycle is coupled through a carry transistor to driving means for the counting tube in the next counting stage to provide a carry pulse therefor. The carry transistor provides the desired carry pulse at its collector electrode. The carry transistor is coupled to the counting tube which controls its operation in such a manner that (1) it provides a carry pulse of the proper time duration and (2) it is held inoperative for a sufficient length of time so that it is prepared to provide a carry pulse each time such is required.

The invention is described in detail by reference to the drawing wherein the single figure is a schematic representation of a circuit embodying the invention.

The counting circuit shown and described is particularly suited for use with magnetron beam switching tubes such as the type 6700 tube and with similar devices sold by Burroughs Corporation and known as BEAM-X switches. These devices are cylindrical in form, but they are shown in linear form as tube 10. The tube 10 has an envelope 12 which contains a central cathode 14 and ten groups of electrodes numbered "1," "2," "3," . . . "9," "0." Each group of electrodes includes a spade electrode 16 and a target electrode 20, and each spade electrode serves to form and hold an electron beam on its corresponding target electrode which provides an output signal from the beam. A switching electrode 22, known as a switching grid and used for switching an electron beam from position to position, is also included in each group of electrodes. In the BEAM-X switch, an auxiliary electrode is provided between each target and the adjacent leading spade, and the auxiliary electrode 35 acts as a current collecting electrode.

The tube 10 also includes suitable means (not shown) for providing an axial magnetic field which combines with electric fields within the tube to form an electron beam and switch it from one group of electrodes to the next. Such means may be an external permanent magnet or internal magnets or the like. The direction in which an electron beam is urged, that is clockwise or counter-clockwise, is called the leading direction, and is always the same and is determined by the orientation of 45 the electric and magnetic fields.

In the circuit shown in the drawing, the cathode 14 of tube 10 is connected through a suitable resistor 24 to a source of reference potential such as ground. The target electrodes 20 are connected, each to one of the indicator electrodes 28 of a type 6844A indicator tube 30. Thus, visual indication of the counting operation may be provided. The targets may also be connected to any other suitable utilization device or circuit.

The switching electrodes 22 are connected in two groups, with the odd-numbered electrodes in one group and the even-numbered electrodes in the other group. Each group of switching electrodes is connected to one of the outputs of a flip-flop 34, the input of which is connected to a suitable source 36 of counting pulses.

According to the invention, the spade electrodes are connected in the following manner. Assuming that a carry pulse is to be transmitted from tube 10 as an electron beam switches from position "9" to position "0," the position "9" is assumed to be the last position in the

counting cycle, and position "0" is assumed to be the first position in a new counting cycle. Accordingly, the spade electrodes at positions "0," "1," "2," and "3" are connected through spade load resistors 38 to a bus 40 which is coupled to a positive D.C. power source V_s . The other spade electrodes at positions "4" through "9" are connected through spade resistors 38 to a bus 44.

A carry pulse amplifier, a transistor 50, is provided for transmitting a carry pulse from tube 10 to the next succeeding tube (not shown) in the counting chain after tube 10 has completed a counting cycle. Because of the polarity of the available electrical signals, the carry pulse amplifier is preferably an NPN transistor having base, emitter, and collector electrodes 51, 52, 53, respectively. The emitter electrode 52 is connected through a diode 57, oriented as shown, to the base electrode 51 and then through a bias resistor 56 to a positive D.C. power source. The diode 57 maintains the potential level of bus 40 and of emitter 52. The emitter electrode is also connected to spade bus 40 through lead 60. The base electrode is also connected through lead 64 to spade bus 44. The collector electrode 53 is connected through a load resistor 68 to the power source V_b and to output terminals 70, from which a carry pulse is derived. The terminals 70 might be coupled to a flip-flop or to any other suitable means for driving the next counting tube.

The circuit shown in the drawing also includes a suitable zero-set circuit 80 coupled to the "0" spade for clearing an electron beam in the tube and resetting it at the "0" position. A typical zero-set circuit operates by first reducing the potential of the spade electrodes to cathode potential to clear the tube and then holding the "0" spade at a potential lower than that of the other spades until a beam forms at the "0" position. The tube 10 might also be cleared by applying a positive pulse to the cathode 14, and then the beam may be reset at the "0" position by the application of a negative pulse to the "0" spade.

In operation of the circuit of the invention, it is assumed that the carry transistor 50 is normally held off. After an electron beam is formed and set at the "0" position, it is then switched from position to position by means of flip-flop 34. The transistor 50 is held off by current flow to its base electrode from the spade electrodes at positions "4" to "9" inclusive. When the beam reaches the last or "9" position and then switches to the "0" position, current flow from spades "4" to "9" is cut off and the spade bus 44 rises to a positive potential which is applied to the base electrode 51 of the transistor 50. The transistor is turned on thereby. As the transistor turns on, it produces a carry pulse at its output terminal 70.

As the electron beam in tube 10 continues to switch under the influence of the flip-flop 34, the beam moves through positions "1," "2," and "3," during which time the transistor 50 remains on and the carry pulse persists. This total time may be of the order of a few microseconds, enough for the next tube to properly utilize the carry pulse. As the beam moves into position "4" and through positions "4" to "9," current flows from the spade electrodes at these positions through bus 44 to the base electrode 51 of the transistor 50 and keeps the transistor turned off. During the time that the transistor is thus held off, the capacitance of the collector electrode 53 and its associated circuitry can be charged and the collector is raised to the positive potential which it normally carries when the transistor 50 is off. Thus, by the time the electron beam again reaches the "9" position, the transistor collector electrode has completely recovered and is prepared to generate the next carry pulse. If the transistor and its collector were not operated in this way, the collector could not generate a carry pulse each time the beam completed a switching cycle in tube 10.

It can be seen that the circuit of the invention provides means for controlling the operation of a pulse carrying

5 circuit between counting tubes and regulating the time during which a carry pulse is available and the time during which the pulse generating circuitry can recover and prepare itself for generating a carry pulse. It is clear that the time distributions described above may be varied as required by rearranging the spade connections.

What is claimed is:

1. A counter circuit including an electron beam switching tube operable as a counting tube and including a cathode and a plurality of groups of electrodes; each group of electrodes including a target electrode which receives an electron beam and produces an output signal therefrom, a spade electrode which holds an electron beam on its associated target electrode, and a switching electrode which serves to switch an electron beam from one group of electrodes to the next;

said cathode being coupled to a source of reference potential;

the switching electrode in each group of electrodes being coupled to a source of switching pulses; the spade electrode in each of a plurality of said groups of electrodes being coupled to a first bus;

the spade electrode in each of other of said groups of electrodes being coupled to a second bus; said first and second buses carrying different and alternating potentials as said tube executes a counting operation;

a transistor having base, emitter, and collector electrodes and provided for generating a carry pulse from said beam switching tube;

said emitter electrode being coupled to a source of reference potential and to said first bus;

said collector electrode being coupled to signal input means;

said second bus being coupled to the base electrode of said transistor whereby said transistor is turned on and off alternately as the potential of said second bus changes during the execution of said counting operation by said tube;

the length of time during which said transistor is on or off being determined generally by the number of groups of electrodes whose spade electrodes are coupled to each bus.

2. The circuit defined in claim 1 wherein the spade electrodes coupled to said first bus are in consecutive groups of electrodes and the spade electrodes coupled to said second bus are in consecutive groups of electrodes.

3. A counter circuit including an electron beam switching tube operable as a counter and having a cathode and a plurality of groups of electrodes; each group including a target electrode which receives an electron beam and produces an output signal therefrom, a spade electrode which holds an electron beam on its associated target electrode, and a switching electrode which serves to switch an electron beam from one group of electrodes to the next; said tube being adapted to execute a counting cycle

as an electron beam flows to each of said groups of electrodes in order with one group of electrodes being designated as the last group in the counting cycle and the next being designated as the first in the counting cycle, the arrangement being such that a carry pulse is to be transmitted when an electron beam switches from said last group to said first group;

said cathode being connected to a source of reference potential;

the switching electrode in each group of electrodes being connected to a source of switching pulses;

the spade electrode in each of said last group of electrodes and of a plurality of groups preceding it in the counting cycle being coupled to a first bus;

the spade electrode in each of the other groups of electrodes including said first group being coupled to a second bus;

said first and second buses carrying different potentials as said tube executes a counting operation with the potentials being effectively reversed as one or the other buses receives current from an electron beam flowing to one of its groups of electrodes;

a transistor having base, emitter, and collector electrodes and provided for generating a carry pulse from said beam switching tube;

said collector electrode being coupled to an output terminal at which a carry pulse appears;

said first bus being coupled to the base electrode of said transistor whereby said transistor is turned on

and off alternately as the potential of said first bus changes during the execution of said counting operation by said tube;

said second bus being connected to the emitter electrode of said transistor;

the length of time during which said transistor is on or off being determined generally by the number of groups of electrodes whose spade electrodes are coupled to each bus.
